CONTROLLING MEANS

Walter S. Landon, Detroit, Mich., assignor to Detroit Lubricator Company, Detroit, Mich., a corporation of Michigan

Application November 8, 1941, Serial No. 418,427

13 Claims. (Cl. 200—122)

This invention relates generally to controlling means and is, among other uses, adapted to control the operation of a fuel burner.

One object of this invention is to provide means for automatically controlling the flow of fuel to a fuel burner.

Another object is to provide means for automatically controlling the supply of air to the burner in accordance with fuel flow.

Another object is to provide an automatic control unit which can be readily applied to a manual fuel control apparatus to render the manual apparatus automatically operable.

Another object is to provide a control device which is particularly adapted for cooperation with the fuel control apparatus.

Another object is to provide means for operation of the fuel control apparatus and the control device by the automatic control unit.

Another object is to provide a control apparatus comprising a unitary structure composed of a plurality of readily assemblable units.

Another object is to provide means to facilitate the operation of the manual means by an automatic means.

These and other objects will be apparent from a reading of the following specification.

The invention consists in the improved construction of and combination of parts, to be more fully described hereinafter and the novelty of which will be particularly pointed out and distinctly claimed.

In the accompanying drawings, to be taken as a part of this specification, there is fully and clearly illustrated a preferred embodiment of my invention, in which drawings—

Figure 1 is a view partially in side elevation and partially in vertical section on the line 1—1 of Fig. 2 showing a controlling means embodying the invention;

Fig. 2 is a top plan view of the controlling means with the cover member of the automatic controlling unit removed and having the casing of the control device in section on the line 2—2 of Fig. 1;

Fig. 3 is a view of one of the automatic units taken substantially along the line 3—3 of Fig. 2 and looking in the direction of the arrows;

Fig. 4 is a bottom plan view of the automatic unit shown in Fig. 3 and having certain of the parts in horizontal section;

Fig. 5 is a bottom plan view of the control device;

Fig. 6 is an enlarged view of the control device having its casing in vertical section and hav-

ing certain parts broken away and in vertical section for clarity;

Fig. 7 is an exploded view of certain of the parts of the control device shown in Fig. 6;

Fig. 8 is a diagrammatic view showing the controlling means of Fig. 1 in side elevation and operatively connected to a fuel burner;

Fig. 9 is a detail view in side elevation of the terminal block for the control device as seen in Fig. 8;

Fig. 10 is a schematic view of the controlling means and wiring diagram of the application of the controlling means to a fuel burning apparatus, and

Fig. 11 is a detail view in section on the line 11—11 of Fig. 6.

Referring to the drawings by characters of reference, the numeral 1 designates the casing of a constant level chamber having an inlet (not shown) which may be controlled by a float operated valve and having in its bottom wall 2 an outlet 3 preferably screw-threaded for connection to a liquid supply line leading to a gravity fed type burner preferably of the pot type. The

liquid supply line is connected to a screw-threaded inlet 3a of a strainer chamber 3b which is positioned against the lower external surface of the wall 2 and communicates with the float valve controlled casing inlet (not shown) for supplying liquid to the constant level chamber. Extending upwardly within the casing from its bottom wall 2 there is a valve housing or casing 4 having a vertically extending vent duct 5 communicating with the outlet 3 and terminating at

its upper end above the liquid level in the chamber. The valve casing 4 has an outlet passageway 6 leading to the outlet 3 and having its inlet end provided with a valve seat member 7 provided with an outlet port 8 having a surrounding annular valve seat 9. The valve casing 4

has a tubular sleeve member 10 extending upward around and laterally spaced from the seat member 7 and terminating above the liquid level within the chamber. Within the sleeve member

10 there is a metering valve member 11 having a conical portion 12 engageable with the seat 9 to close the outlet passageway 6. The valve member 11 also has a cylindrical end portion 12a

which fits the port 8 and has one or more metering slots 13 with a communicating pilot slot 14, which slots cooperate with the wall of the port 8 to regulate or meter flow from the chamber. A helical coil spring 15 surrounds the valve mem-

ber 11 and the seat member 7 and acts upward against a collar or flange 16 on the valve mem-

ber 11 to urge the valve member 11 toward open position. The collar 16 is rotatably supported in an annular groove 17 in the valve operating rod or stem 18 and has a finger 19 fitting and guided within a vertical slot 20 through the wall of the sleeve member 10 to hold the collar 16 against rotation upon rotation of the stem 18. The slot 20 provides an inlet to the valve casing and port 8 for flow from the constant level chamber.

Overlying the housing 4 and spaced thereabove, there is a bridge or supporting member 21 which extends across the chamber and is supported at either end upon spaced stepped bosses or posts (not shown) projecting inward from the side walls of casing 1. Overlying and spaced above the bridge member 21 there is a cover member 27 which closes the top of and provides a top wall for the casing 1 and which may be secured in position by screws 28 and 28a (Fig. 2) threaded into bosses (not shown) integral with the walls of the casing 1. The bridge member 21 has an upwardly extending tubular guide member 29 concentric with an aperture through the bridge member and aligning with the port 8. The stem 18 extends upward through the bridge member aperture and the guide member 29 in which it is rotatably and reciprocally guided. Through the cover member 27 there is an aperture 30 aligned with the guide member and port 8 and through which extends the upper end of stem 18 and the sleeve like portion of a hand grip member 31 which is secured to the stem by a screw 32 so that the stem 18 is positively rotatable by the hand grip member.

Positioned at diametrically opposite points relative to the valve member 11 and spaced circumferentially and laterally thereof, there are supporting bosses 33 (one of which is shown) which are rigid with the casing 4. The upper ends of the bosses 33 are longitudinally screw-threaded to receive upwardly extending screw-threaded rods or posts 35, 36. The post 35 extends upward through aligned apertures 37, 38 in the bridge member 21 and cover member 27 respectively, the aperture 38 providing guide means for the upper end of post 35 which is provided with a kerf or screw driver receiving and adjusting slot (Fig. 2). The post 36 extends upward through apertures 39 and 40 in the bridge member 21 and cover member 27 respectively, the aperture 40 providing a guide means for the upper end of post 36 which is provided with a kerf or screw driver receiving and adjusting slot.

The cam means for operating the valve member comprises a follower member 42 cooperable with cam track members 43, 44 carried by or on the posts 35, 36. The follower member 42 may be a short cylindrical rod projecting radially from the valve stem between the valve housing 4 and bridge member 21. The track members 43, 44 are of resilient sheet material preferably annealed sheet steel. The track member 43 has a curved track portion 45 of helical form with a low point or portion 46 and a high point or portion 47 at its opposite ends. Projecting from the track member 43 adjacent the low portion 46 there is a positioning and supporting ear 48 which is bent upward to lie in a horizontal plane above its adjacent track portion and having a circular aperture therethrough receiving and fitting the post 35. Extending upward from the high cam track portion 47 and opposite the ear 48 there is a positioning and supporting ear 50 bent to lie in a horizontal plane above the high point 47 and in a plane parallel to the plane of the ear 48. The

ear 50 has an elongated aperture therethrough to receive the post 36 and provide for adjustment, the aperture in ear 50 being diametrically opposite the aperture in ear 48. The jointure of the ears 48 and 50 with their respective cam track portions is preferably of small cross-section so that upon adjustment of the ears, as will be described hereinafter, the jointures will provide a flexible connection between the ears 48 and 50 and their respective cam track portions. The track member portion 45 which is formed as a portion of an annulus is concentric with the valve member 11 and therefore partially surrounds the same. Projecting upward from the ear 50 at its side opposite the track portion, there is a stop arm or member 52 which extends through the bridge member aperture 39 and is parallel to and spaced laterally from the post 36.

The track member 44 has a track portion which is of generally arcuate form in plan view and terminates at its ends in positioning and supporting ears 53, 54 respectively, the ear 53 having a cylindrical aperture to receive and fit the post 35 and the ear 54 having an elongated aperture to receive the post 36 and provide for adjustment, the ear 53 overlying the ear 48. Intermediate its ends the track member 44 has a downward stepped or offset portion providing steps 57, 58, the riser portion of the upper step 57 substantially abutting the low end of track member 43 and cooperating with the low point 46 to form a stop shoulder at the low end of the track portion 45. The downward facing horizontal portion of step 58 cooperates with the follower member 42 to lock or hold the conical valve portion 12 tightly against its seat 9. The arcuate or curved end portions of the track member 44 provide sufficient flexibility so that the step 58 can move upward to receive the follower member 42 and thereby resiliently press the valve to its seat. The riser portion 59 of the step 58 serves as an abutment or stop for engagement by the follower member 42 to limit final rotary movement of the valve member 11 when it has been seated in full closed position.

Secured on the posts 35, 36 there are abutment members or collars 60, 61 respectively, providing downward facing shoulders and having stop fingers (not shown). These abutment members are of similar construction and therefore the description of one will suffice for both. The member 61 comprises a sleeve member 64 which fits the post 36 and against which the track member 43 abuts upwardly. The member 64 is held in its position on the post by a flanged member 65 from which the stop finger (not shown) extends for engagement with the stop arm 52. With the stop finger of the member 61 positioned in engagement with the rear edge of stop arm 52, the member 61 is moved up or down on post 36 until, with the follower member 42 at the track high point 47, the valve member 11 will have its maximum desired open or flow position. The flanged member 65 is then permanently secured to the post 36 as by solder or the like. The track high point ear 50 is held up against the sleeve member 64 by a coil spring 67 surrounding the post 36 and bearing at its lower end upon the ear 54 of track member 44 so that the ear 54 is urged downward against or toward the valve casing 4 and the step 58 is urged toward the valve closed position. Rotation of post 36 so that the stop finger of the flanged member 65 moves away from arm 52, by clockwise rotation facing Fig. 2, will move the abutment member 61 downward thereby lowering the high point 47 of the cam track portion 45. This

permits of an adjustment from the maximum safe flow rate to a lesser maximum rate. The collar or abutment member 60 is slid up or down on post 35 until, with the stop finger of member 60 against its stop (not shown) and with the follower member 42 on the cam low point 46 and against step 51, the cam low point 46 is positioned to obtain the largest minimum or maximum pilot flow desired through slot 14. The abutment member 60 is then soldered or otherwise securely fastened to the post 35 and thereafter upon rotation of post 35 in a clockwise direction facing Fig. 2 the cam low point 46 will be lowered thereby decreasing the rate of minimum or pilot flow through the valve. The clockwise adjustment of post 35 and the lowest flow rate obtainable by this adjustment is limited by engagement with a stop (not shown) of the finger carried by the flange member of collar 60. The cam track members 43, 44 are held up against abutment member 60 by a coil spring 68 which surrounds post 35 and seats on the upper end of boss 33. The springs 67 and 68 are under compression and exert sufficient force to hold the ends of the track members 43, 44 normally in rigid fixed position. Upon rotation of post 35 to adjust the cam low point 46, the track member 43 will be flexed adjacent the jointure of the ear 50 with the track portion 47 so that the cam high point 47 will remain in its fixed position. Upon rotary adjustment of post 35, the track member 43 will flex adjacent the jointure of the ear 48 with the track portion 46 so that the position of the cam low point 46 will remain fixed as the high point is varied or moved. The underside or follower engagement face of track portion 45 may be provided with equally spaced radial serrations or notches (not shown). These serrations are preferably only deep enough to hold the follower member against shifting from its set position which might result from vibration or touching of the grip member 31.

In order to limit the opening movement of the valve member 11 and prevent rotational movement of the follower member 42 beyond the high point 47, a stop member (not shown) extends downward from the bridge 21 adjacent its aperture through member 29 through which stem 18 extends. This stop member extends downward sufficiently so that the follower member cannot by downward reciprocation of the valve stem upon compression of the spring 15 be thereafter rotated in further counter-clockwise movement.

A second valve member 69 having a hand grip member 70 similar in all respects to the valve member 11 and hand grip member 31 may be provided in the apparatus for providing dual outlets from the casing 1. To simplify this specification and because the two valve members 11 and 69 are substantially identical, the parts of the valve member 69 will be referred to by the same numerals with the exponent "a" added unless otherwise noted and the details of valve 11 only will be shown. It will be noted however that it is discretionary as to whether the second valve member is to be provided or not and depends upon the burner to be controlled.

The operation of the valve as so far described is as follows: With the constant level chamber connected to a suitable source of oil supply and the outlet 3 connected to the burner or the like, the low point 46 is adjusted within the minimum limit range by rotation of post 35 to provide proper flow through slot 14 for pilot fire and the cam high point 47 is adjusted by rotation of post 36 within its range of maximum adjustment to

determine the maximum flow rate through slots 13 to the burner. Either the minimum or the maximum open position of the valve member 11 may be thus adjusted as above described without altering the other position. The valve member 11, when rotated to closed position as above noted, is urged to its seat by the resilience of track member 44 and the spring 67 so that the step shoulder 58 which has been lifted by the follower member 42 is acting through the follower member 42 to hold the valve member tightly seated. As the valve member 11 is rotated by the hand grip 31 in a counter-clockwise direction or toward open position any dirt on the seat will be sheared by rotation of the spring loaded valve. When follower member 42 passes from under the track portion 58 which leads it to the cam low point 46, the valve member 11 will have a quick opening movement as the follower member rises to engage the cam low point. There will now be pilot flow at the minimum desired rate through the pilot slot 14. As the follower member 42 leaves the track member 44, the track member 44 may have some downward movement but this will not disturb the setting of the cam low point which is at all times held in set position by spring 68 and the opposing abutment member 60. The valve member 11 is now freely movable toward further open position under the force of spring 15 as the follower member 42 is moved counter-clockwise along the underside of track portion 45, the serrations therein not being of sufficient depth to impede the continuous rotation of the valve member 11. When the valve member 11 has been moved to full open position as determined by the positioning of abutment member 61, then the follower member 42 will be on the cam high point 47 and substantially in engagement with the stop member.

The valve operation however may be transformed into automatic operation by the addition of a valve actuating mechanism generally designated 100 and a switch mechanism generally designated 101 which may be attached as independent units to the top wall of the casing 1 and positioned against the cover member 27. The actuating mechanism 100 comprises a hollow casing 102 conforming in contour with the casing 1 and having an open top wall 103 and an open bottom wall. The casing 102 in horizontal cross section is generally U-shaped with an end wall 104 having extending side walls 105, 106 projecting therefrom and flaring outwardly. The walls 105, 106 at their end portions are joined by a connecting end wall 107. The top wall 103 is closed by a cover 103^a secured thereto as by thumb screws 107^a threaded into apertured bosses 107^b integral with the walls 105 and 106. The casing 102 has apertured projecting bosses 108, 109 extending from and in the plane of its lower end wall and which are positioned respectively at the intersection of the walls 105, 106 with the wall 107. The bosses 108 and 109 receive the screws 28 which act to secure the casing 102 to the chamber 1. The wall 107 has a forwardly projecting abutment 109^a which is adapted to seat against the top surface of the cover member 27 to prevent cocking of the casing 102. The wall 107 adjacent the lower end wall of casing 102 has a plurality of inwardly extending lugs 111, 112 and 113 which extend from the wall 107 toward the opposite end wall 104 and which have aligned V-shaped slots for receiving a rod or fulcrum member 114 which extends between the walls 105 and 106 spaced from and substantially parallel to the cover member 27. Each of the lugs 111, 112 and 113 have

threaded apertures therethrough in which are screw-threaded upwardly extending screws 115, 116 and 117 respectively, and which screws have head portions adapted to engage the fulcrum member 114 to rigidly hold the fulcrum member 114 within the aligned V-shaped apertures. A bell-crank lever member 118 is preferably fabricated from a piece of substantially T-shaped sheet metal by bending one of the arms or oppositely extending portions 119 at right angles to the plane of the metal and then bending the end portion 120 of this oppositely extending portion into a plane substantially parallel to the plane of the sheet metal so that it extends in the same direction as the other of the oppositely extending portions. The other of the oppositely extending portions or arms forms one leg 121 of the bell crank lever member 118. The portion 120 and leg 121 have aligned apertures for receiving the rod member 114 so that the member 118 may be rotated thereabout. The horizontal stem or standard portion of the T-shaped piece forms the other leg 122 of the bell crank member 118 and extends through an aperture in the wall 107 and has an abutting portion 122^a abutting an upwardly facing shoulder 122^b of the grip member 31. The bell crank member 118 is positioned between the lugs 111 and 112 and has an extending conical portion 123 projecting from the leg 121 in a direction opposite to the direction of the leg 122. The conical portion 123 is positioned intermediate the upper or free end portion of the leg 121 and the fulcrum member 114. A second bell-crank lever member 124 is constructed similarly to the lever member 118 except that it is a mirrored or reflected representation thereof. The member 124 is fulcrumed on the fulcrum member 114 intermediate the lugs 112 and 113 and comprises a first leg 125, a second leg 126 which extends through an aperture in the wall 107 and an extending conical portion 128. The second leg 126 has an abutting portion 126^a which overlies an upwardly facing shoulder 127 of the grip member 70. The legs 121 and 125 have adjacent their free ends aligned apertures for loosely receiving a horizontally extending cross bar or connecting rod 128^a. Extending from the side walls 105 and 106 and spaced slightly above the cover member 127, are a pair of inwardly extending lugs 129 and 130 respectively. The lugs 129 and 130 have screw-threaded apertures extending therethrough which face the conical portions 123 and 128 respectively. Screw-threaded within these apertures are a pair of adjusting pin members 131 and 132 respectively, having conical end portions facing the conical portions 123, 128 respectively. Apertures 132^a extend through the side walls 105 and 106 adjacent the outer ends of the members 131 and 132 opposite their conical end portions so that the pin members 131 and 132 may be screw-threaded within the lugs 129 and 130 from externally of the casing 102. After adjustment, the screws or pin members 131 and 132 may be held in position by set screws 131^a and 132^b. Spring abutment members 134, 135 are positioned respectively against the conical portion 123 and conical end portion of the member 131 and a helical coil compression spring 136 is held under compression therebetween. To prevent buckling of the spring 136, the abutment member 135 is provided with an extending guide finger or pin which is received within and is reciprocal within a guide aperture of the abutment member 134. In like manner, an abutment member 139 is positioned against the pin member 132 and an abut-

ment member 140 is positioned against the conical portion 128 for engagement by the ends of a helical coil spring 141 which is held under compression therebetween. The abutment members 139 and 140 have respectively a guide aperture 142 and a cooperating extending portion 143, which prevent buckling of the spring 141 and are identical to the cooperating element of the members 134 and 135.

10 The position of the conical portions 123 and 128 are so chosen relative to the position of the pin members 131 and 132 and to the fulcrum member 114 that when the bell-crank members 118 and 124 are rotated to their extreme clockwise positions (see Fig. 1) the conical portions 123 and 128 maintain a position above an imaginary line drawn between the fulcrum member 114 and the conical portion of the pin members 131 and 132. The helical coil springs 136 and 141 therefore continuously act to urge the valve members 11 and 69 in a valve closing direction against the opening force of the springs 15 and 15^a.

15 The side walls 105 and 106 have vertically extending bosses 144, 145 and 146, the upper ends of which terminate below the top wall 103 and provide seating surfaces for a plate-like supporting member 147 which has a contour substantially conforming to that of the casing 102 and which is preferably of an insulating material such as 20 "Bakelite." The plate-like supporting member 147 is held against the upper end surface of the bosses 144, 145 and 146 by means of screws 144^a, 145^a and 146^a which extend through apertures in the plate-like member 147 and are screw-

25 threadedly received within apertures opening upwardly through the upper end surfaces of the bosses 144, 145 and 146. A bimetallic actuating element 148 is carried by and on the lower surface of the plate-like supporting member 147

30 substantially midway between the walls 105 and 106 and adjacent the wall 107. The bimetallic actuating element 148 is fixed to a substantially U-shaped supporting member 149 having one of its legs 150 secured as by screws 151 to the supporting member 147 and having its base portion held as by a screw 151^a to the wall 107. The sensitive portion of the bimetallic actuating element 148 comprises a bimetallic strip member 35 having one end portion bent into a substantially cylindrical portion 153. The other end portion extends from the portion 153 as a radially extending lip portion 154. The end portion of the cylindrical portion 153 spaced from the lip portion 154 is secured to the other arm 155 of the 40 U-shaped member 149 in any suitable manner, such as by welding. The lip portion 154 is spaced from the wall 107 and extends downward toward the bottom wall of the casing 102 and engages an enlarged diameter portion 155^a of the connecting rod 128^a substantially midway between the bell-crank lever members 118 and 124. The portion 155^a has a central circumferential recessed portion 157 which receives an embossed or raised projecting portion 158 of the lip portion 154.

45 An electrical resistance heater 159 is positioned within the cylindrical portion 153 and has lead wires 160, 161 extending therefrom and connected to a terminal rivet 162 and to a post 163 respectively, carried by and extending through 50 the plate-like supporting member 147.

55 A transformer unit 164 of conventional design has at its upper end portion outturned flanges 165, 166, which seat against the lower surface of the plate-like member 147 and are held thereto 60 as by screws 167 so that the unit is within the 65

70

casing 162. The secondary coil lead wires 168, 169 of the transformer 164 are connected respectively to a binding post 170 carried by the supporting member 147 and to the rivet 162. The binding posts 163 and 170 have wire attaching screws 171, 172 respectively, on the top or outer face of the supporting means 147 and which are adapted to receive the lead wires 172^b, 172^a from a room thermostat 173 for controlling the circuit to the heater 159 of the bimetallic actuating element 148. The primary coil of the transformer 164 is connected by means of lead wires 174, 175 of an electrical cord 176 to a conventional male plug 177. The end of the cord 176 is rigidly held adjacent the transformer 164 by means of a clamp 178 which has an outstanding projecting portion 179 received within a slot (not shown) in the flange 165. The lower portion of the clamp 178 is held by means of a bolt and nut 181 to the transformer 164 and which bolt and nut 181 acts to hold the transformer core together. To additionally hold the cord 176 in place, an L-shaped member 181^a has its longer leg positioned against the upper surface of the member 147 and held thereto by one of the screws 167. The shorter leg of the member 181^a extends downward and has an aperture therethrough through which the cord 176 extends and in which it has a snug fit.

The flanges 165 and 166 have screw-threaded apertures extending therethrough aligning with rectangular apertures 165^a, 166^a in the supporting member 147 and overlying substantially horizontally projecting portions 182 and 183 of the lever members 118 and 124 respectively. Low fire adjusting screws 184 and 185 are screw-threaded respectively within the screw-threaded apertures in the flanges 165 and 166 respectively, and have upper end portions extending through the plate-like supporting member 147. The upper end portions have screwdriver slots or kerfs for reception of a screwdriver or other suitable tool for rotating the low fire adjustment screws 184 and 185. Nuts 184^a and 185^a are screw-threaded onto the screws 184 and 185 respectively so that they are positioned within the rectangular apertures 165^a and 166^a and held thereby against rotation with the screws 184 and 185. Lock washers (Fig. 1) positioned intermediate the nuts 184^a and 185^a and the flanges 165 and 166 are held under compression thereby so that the screws 184 and 185 are frictionally held against rotation relative to the flanges 165 and 166. The lower end portions of the adjusting screws 184 and 185 are engaged by the extending portions 182, 183 respectively upon predetermined counter-clockwise movement of the lever members 118 and 124 (see Fig. 1) to limit valve closing movement of the valve members 11 and 69 respectively, by the lever members 118 and 124. The adjusting screws 184 and 185 are respectively journaled adjacent their lower end portions within apertures in outwardly extending flange portions of L-shaped members 182^a and 183^a held to the transformer core as by a bolt and nut 182^b which also holds the core together.

It will be noted that as the bell-crank lever member 118 rotates clockwise, the conical portion 123 moves nearly into alignment with the fulcrum member 114 and the conical end portion of the pin member 131 so that the spring 136 while exerting an increasing total force will exert a decreasing component of force opposing this clockwise rotation. The spring 136 is so

chosen relative to the angle at which it acts on the lever member 118 and to the spring 15 that the decrease in its moment of force opposing clockwise rotation is somewhat more than the decrease in moment of force exerted by the spring 15 due to its "scale per inch". This construction provides in effect a negative "scale per inch" for the spring 15. Furthermore the magnitude of the moment of force exerted by the spring 136 is always less than the moment of force of the spring 15. The positioning of the conical portion 123 and the magnitude and "scale per inch" of the springs 141 and 15^a are so selected that the bell-crank lever member 124 is actuated in a like manner as described relative to the bell-crank member 118. It therefore follows that were these the only forces acting on the bell-crank lever members 118 and 124, the valve members 11 and 69 would always remain in an open position limited only by the engagement of the follower member 42 with the track member 43. The bimetal element 148, however, acts to exert its force against the enlarged diameter portion 155^a of the connecting rod 128^a and provides the necessary force to overbalance the sum of the moments of force exerted by the springs 15 and 15^a respectively, on the lever members 124 in excess of the opposing moments of force exerted by the springs 136 and 141. As the element 148 increases in temperature due to heating by the heater 159, the force exerted by the lip portion 154 urging the lever member 118 and 124 in a counter-clockwise direction, decreases until the clockwise moment exerted by the springs 15 and 15^a slightly exceeds the total counter-clockwise moments of force. When this occurs, the lever members 118 and 124 are rotated gradually in a clockwise direction by the springs 15 and 15^a. As stated hereinbefore, upon clockwise rotation of the lever members 118 and 124 the counter-clockwise moment of force exerted by the springs 136 and 141 decreases at a greater rate than the decrease of clockwise moment of force exerted by the springs 15 and 15^a due to their "scale per inch." This net increase in clockwise moment of force on the lever members 118 and 124 is substantially compensated for by the "scale per inch" of the resiliency of the element 148 as it is moved by the connecting rod 128^a. The result is that upon initial movement of the lever members 118 and 124 in a clockwise direction upon heating of the element 148, the valve members 11 and 69 will move gradually toward open position but will not move throughout their entire range of allowed movement until the element 148 is heated gradually to a higher temperature. It may now be understood that with the construction and operation hereinbefore described, the valve members 11 and 69 will be urged by the springs 15 and 136, and 15^a and 141 respectively toward open position with a progressively increasing force so that the valve members 11 and 69 will be moved to a further open position than would otherwise be permitted due to the heating of the element 148. The magnitude of this extra opening valve movement is determined by the "scale per inch" of the element 148 as it is flexed by the additional net moment of clockwise force exerted by the springs 15, 15^a, 136 and 141.

After deenergization of the element 148, the bimetallic cylindrical portion 153 commences to cool. Upon cooling to a predetermined temperature, less than the temperature of the element 148 at the time the valve members 11 and 69

were moved into the maximum open position, the element 148 will be stressed a sufficient amount from its free position so that the counter-clockwise moment of force exerted thereby on the lever members 118 and 124 due to the "scale per inch" of the element 148 is sufficient to overcome the net clockwise moment of force exerted on the lever members 118 and 124 by the springs 15, 15^a, 136 and 141 so that the valve members 11 and 69 are moved toward closed position. This movement toward closed position will be at a greater rate than the rate of the change in the free position of the element 148 upon cooling of the portion 153 due to the decrease in clockwise moment of force caused by the effective negative "scale per inch" of the springs 15 and 15^a as hereinbefore described in connection with the opening movement. In other words, the counter-clockwise moment of force which must be supplied by the element 148 decreases as the valve members 11 and 69 move toward closed position and therefore the force which the element 148 supplies because of its displacement from its free position and its "scale per inch" decreases with the before named result of moving the valve members 11 and 69 toward closed position faster than the movement of the free position of the element due to the cooling of the portion 153. The valve members 11 and 69, however, will not be moved toward closed position with a snap movement or without continued cooling of the element 148 because the effective negative "scale per inch" of the springs 15 and 15^a is not of sufficient magnitude to completely compensate for the "scale per inch" of the element 148.

It may now be readily understood that the co-operation of elements hereinbefore set forth provide a means for operating a valve or other reciprocal member by a power element exerting a relatively small force in respect to the resistance to movement exerted by the valve or reciprocal member. These elements also provide an actuator which permits a greater degree of movement of the reciprocal member than the movement afforded by the normal movement of the actuator even when changes in movement due to levers are considered.

Should the valve member 69 be omitted and the mechanism 100 used to control a valve mechanism with only a single valve 11, then the moment of force exerted on the lever member 124 in a clockwise direction will be nil and the member 124 will remain in a fixed position with the extending portion 183 in engagement with the low fire adjusting screw 185. Due to the loose connection between the connecting rod 128^a and the leg 125, the rod 128^a acts as a lever member fulcrumed at the point of connection with the leg 125 so that the net clockwise moment of force exerted by the lever member 118 on the rod 128^a acts to pivot the rod 128^a about the leg 125. The force exerted by the lever member 118 is substantially one-half of the total force exerted on the lip portion 154 when both lever members 118 and 124 are actuating valves. Therefore as the bimetallic element lip portion 154 engages the rod 128^a substantially midway between the lever members 118 and 124, the force exerted on the lip portion 154 will be the same whether one or both of the lever members 118 and 124 are operating or not, the only difference being that in case the mechanism 100 is on a single valve instrument the travel of the lip portion 154 will

be one-half of that of the travel when a dual valve instrument is used.

The switch mechanism 101 is attached as an independent unit to the top wall of the casing 1 at the end thereof opposite to the mechanism 100. The switch mechanism 101 comprises generally a rectangular casing 199 having side walls 200 and 201, end walls 202 and 203, a closed upper end wall 204 and an open lower end. The lower end of the casing 199 has flanged portions 205, 206 extending perpendicular from the side walls 200 and 201 which seat against the cover member 27 and have contours substantially conforming to the contour of the casing 1. The screw 28^a extends through the flange portion 205 and securely clamps the mechanism 101 to the casing 1. A substantially rectangular switch unit 208 is positioned within the casing 199 and has adjacent one end portion an aperture extending therethrough. A rod or fulcrum member 207 having reduced end portions is carried within and fits this switch unit aperture and extends beyond each face of the unit 208, see Fig. 11. A pair of lever members 209, 210 have apertures 209^a adjacent one end portion through which the fulcrum member 207 extends and in which the member 207 fits. The lever member 209 is positioned intermediate the switch unit 208 and the side wall 201 and the lever member 210 is positioned intermediate the switch unit 208 and the side wall 200. The lever members 209 and 210 have respectively extending portions 211 and 212 which extend through apertures 213, 214 respectively, in the end wall 202 and engage the upwardly facing shoulders 122^a and 127 of the grip members 31 and 70 respectively.

The rectangular switch unit 208 has an operating push button 215 which is operable upon downward movement into the switch unit 208 to actuate the switch and establish a circuit between the lead wires 216, 217 connected thereto. A U-shaped member 218 fits over the rectangular switch unit 208 and has at its open end portion extending portions 219 which extend along the side walls of the switch unit 208 and have aligned apertures 219^a for receiving and fitting on the fulcrum member 207. The open ends of the U-shaped member 218 have apertures 219^b aligned with an aperture 220 extending through the switch unit 208. A pin member 221 extends through the aperture 220 and through the aligned apertures 219^b in the U-shaped member 218 so that the U-shaped member 218 is held against movement relative to the switch unit 208. The base portion of the U-shaped member 218 has a plate-like extending finger 222 which overlies and extends substantially parallel to the top wall of the switch unit 208, the free end portion thereof overlying the push button 215. A pair of bell-crank lever members 223 and 224 are fulcrumed on the member 207, the bell-crank lever member 223 being intermediate the lever member 209 and the side wall 201 and the bell-crank lever member 224 being intermediate the lever member 210 and the side wall 200. The bell-crank lever members 223 and 224 have their upstanding arms 223^a and 224^a projecting above the top wall of the switch unit 208 and beyond the top surface of the finger 222. The upward extending arms 223^a and 224^a of the lever members 223 and 224 are preferably joined by a bridge member 225 so that the movement of the lever members 223 and 224 will be in unison. The bridge member 225 overlies the push button 215. Preferably finger 222 has an aperture overlying the push button

215 and in which is positioned an abutment member 226 having a flat lower surface engageable with the top surface of the push button 215 and a recessed portion in its upper surface. The bridge member 225 has a threaded aperture therethrough in which is screw-threaded a stub screw 227 having a screwdriver slot in its upper end portion and a recess in its lower edge portion. A helical coil compression spring 228 is held under compression between a spring abutment member 229 and a second spring abutment member 230. The abutment members 229 and 230 have extending rod-like portions which terminate in conical surfaces for engagement with the recessed portions of the screw 227 and member 226 respectively. The horizontally extending arms of the bell-crank lever members 223 and 224 have rectangular apertures 231 through which the pin member 221 extends and cooperates to limit rotational movement of the lever members 223 and 224 relative to the switch unit 208. The lever members 209 and 210 also have apertures 232 therethrough through which the pin member 221 extends and through which stub abutment pins 233 carried by the horizontal arms of the bell-crank members 223 and 224 also extend. The apertures 232 have shoulder portions 232a for engagement with the pin 233 so that upon predetermined counterclockwise movement of the lever member 209, the shoulder portion 232a will engage the pin 233 and rotate the lever members 223 and 224. Engagement of the walls of the apertures 231 and 232 with the pin member 221 merely act as a limiting means to prevent movement of the respective lever members beyond the desired degree. The apertures 231 act to limit counter-clockwise rotation of the lever members 223 and 224 so that the point of engagement of the abutment member 229 with the screw 227 does not pass beyond the line of center of the point of engagement of the abutment member 230 with the member 226 and the fulcrum member 207.

The "scale per inch" of the spring 228 is so chosen relative to the angle at which it acts that upon counter-clockwise movement of the bell-crank lever members 223 and 224, the component of force exerted in a direction opposing the counter-clockwise movement of the lever members 223 and 224 is substantially the same at the end of its movement as at the beginning of its movement so that the force required to move the lever members throughout their range of movement will be as nearly constant as possible.

Upon upward movement of the valve members 11 and 69 the shoulder portions 232a will engage the abutment pin 233 and continued counter-clockwise rotation of the lever members 209 and 210, due to continued upward movement of the valve members 11 and 69, will rotate the lever members 223 and 224 counter-clockwise. This counter-clockwise rotation of the lever members 223 and 224 will move the point of engagement of the member 229 and screw 227 more nearly into alignment with the line of centers through the fulcrum member 207 and the point of engagement of the members 226 and 230 with a consequent shortening of the spring 228. The spring 228 will therefore exert a greater component of force downward on the push button 70 or pin 215 due in part to the change in angle at which the spring 228 acts and in part to its "scale per inch." This increase in downward force component is sufficient to push the pin 215 downward to actuate the switch unit 208. Should one of 75

the valve members 11 or 69 be adjusted to open further than the other of the valve members, the valve member opening the further will continue to rotate the lever members 223 and 224 and the abutment pin 233 which cooperates with one of the lever members 209 or 210 resting on the valve member which moves the lesser amount, will rise from its shoulder portion 232a into the aperture 232. A lost-motion connection is therefore had between the lever members 223, 224 and lever members 209 and 210.

The extending portions 219 have downwardly extending ears 233a having aligned apertures for receiving a fulcrum pin 233b. The pin 233b is held at either end within apertures in the walls 200 and 201 and extends substantially normal thereto. A spring 234 has a coiled portion 235 coiled about the fulcrum pin 233b and has one extending portion 234b abutting lower surface of the switch unit 208 and the other end portion 234a abutting the lower surface portion of the end wall 203. The spring 234 acts to urge the switch unit 208 in a counter-clockwise direction about the fulcrum member 233b and into abutting engagement with the lower end surface of an adjustable thrust member 236 which is screw-threadedly received within an aperture through the upper end wall 204 of the switch mechanism 101 and which serves as an adjustment to be hereinafter described. To prevent accidental rotation of the thrust member 236, a lock nut 237 may be threaded onto the member 236 external of the top wall of the mechanism 100 and beneath a manual hand grip portion 238 of the thrust member 236 for abutting the wall 204.

The switch unit 208 may be positioned by means of the thrust member 236 so that the switch unit 208 may be actuated at any desired position of the valve members 11 and 69. If the threads on the member 236 are right hand, clockwise rotation of the member 236 (Fig. 6) will rotate the unit 208 in a clockwise direction about the fulcrum pin 233b to cause the lever members 209 and/or 210 to actuate the unit 208 at a position of the valve members 11 and/or 69 corresponding to a smaller fluid flow. Counter-clockwise rotation of the member 236 produces the opposite result.

Secured to the wall 201, as by screws 239, 50 there is an electrical terminal block 240 (Fig. 9) having a male connection 241 for reception of the female end 242 of an electrical extension cord leading from a source of electrical energy such as the usual 110 volt household supply. The block 240 also has a first female connection 243 which is adapted to receive a male connection 244 of a fan motor unit 245 which supplies forced air to the burner supplied by the outlet 3. If desired the switch 208 could also be used to control a circulating means for the medium heated by the fuel burner. A second female connection 246 of the block 240 is adapted to receive the plug 177 of the mechanism 100. Suitable indicia is preferably inscribed on the outer surface 65 of the block 240 for indicating the respective function of the connection 241, 243 and 246. One terminal 247 of the connection 241 is connected by a lead wire 248 to one terminal 249 of the connection 246 and by a branch lead wire 250 to one terminal 251 of the connection 243. The other terminal 252 of the connection 241 is connected by a lead wire 253 to the other terminal 254 of the connection 246. The lead wire 216 connects one terminal of the switch unit 208 to the lead wire 253 while the lead wire 217 con-

ncts the other terminal of the switch unit 208 to the other terminal 255 of the connection 243.

Should the burner supplied from the outlet 3 not require a controlled means to supply additional air to the burner for increased fire operation thereof such as a pure natural draft burner, the switch mechanism 101 may be omitted and the plug 177 would in that case be attached directly to the female end 242 or to any convenient house receptacle of the proper voltage.

In Fig. 10 there is shown a schematic representation of the invention having a single valve member 11, the valve member 69 being omitted. As far as possible, like parts are designated with the same numerals as are used in the other figures. Current from a suitable source is supplied through the lead wires 256 to the fan unit 245 and through lead wires 248 and 174 to one side of the primary coil of the transformer unit 164. The other side of the current supply is connected by lead wire through lead wire 216 to one terminal of the switch unit 208 and through lead wire 175 to the other terminal of the primary coil of the transformer unit 164. The lead wire 217 connects the other contact member of the unit 208 to the fan unit 245.

The operation of the apparatus is as follows: With the parts positioned as shown in the drawings, the temperature of the space heated by the burner is at or above the predetermined desired degree of temperature. As the space temperature falls, the thermostat 173 acts to complete the electrical circuit of the transformer secondary and current will flow through lead wires 168 and 172^a, the thermostat 173, lead wires 172^b and 161, the heater 159 and lead wires 160 and 169 back to the other side of the secondary coil of the transformer unit 164. The current flowing through the heater 159 acts to heat the cylindrical portion 153 of the bimetallic element 148 so that the lip portion 154 exerts a progressively decreasing force against the connecting rod 128^a to cause the valve member 11 and/or 69 to move upwardly. In the schematic drawing of Fig. 10, the lip portion 154 acts directly on the leg 122 whereas in the actual embodiment of the valve actuating mechanism 100 the lip portion 154 exerts its force against the horizontally extending connecting rod 128^a. Upward movement of the valve member 11 rocks the lever member in a counter-clockwise direction. Such movement of the lever member 209 causes the lower edge of the aperture 232, that is, the shoulder portion 232^a, to engage the underside of the abutment pin 233 which acts to rotate the bell-crank lever members 223 and 224 in a counter-clockwise direction about the fulcrum member 207. Movement of the lever members 223, 224 moves the bridge member 225 more directly into alignment with the abutment member 226 thereby compressing the spring 228 sufficiently so that the spring 228 exerts an increasing downward component of force to push in the push button 215 to establish a circuit between the lead wires 216 and 217. Upon closure of the circuit by the switch unit 208, current flows from the lead wire 256 through the fan unit 245, through the wire 217, switch unit 208 and lead wire 216, back to the lead wire 257 to cause the fan unit 245 to supply the additional air required by the additional fuel supplied by the valve member 11 through the outlet 3 to the burner. The valve members 11 and 69 are shown in Fig. 2 as being set for substantially the same rate of fuel flow. This device operates equally well upon change in relative setting of

fuel flow between the valve members 11 and 69. As far as the mechanism 100 is concerned, the operation of the valve members 11 and 69 when set at unequal flow rates is accomplished by means of the loose connection of the horizontally extending connecting rod 128^a with the legs 121 and 125 which allows for independent rotation of the lever members 118 and 124. As to the switch mechanism 101, this unequal flow rate operation is accomplished by means of the lost-motion connection between the lever members 209 and 210 and the unitary movable lever members 223, 224 so that whichever lever member, 209 or 210 is moved farther in the counter-clockwise direction will cause the abutment pin 233 to be moved into the aperture 232 and out of contact with the shoulder portion 232^a.

It may thus be understood that this invention provides a plurality of separate units which may be assembled by one unskilled in the art to revamp a manually operable burner controlling means into an automatically operable burner controlling means. Furthermore, this is accomplished with only minor changes in the normal household electrical wiring which may be made by the householders themselves.

What is claimed and is desired to be secured by Letters Patent of the United States is:

1. In an apparatus of the character described, a hollow casing having a top wall opening and having an end wall with an aperture therethrough, a lever member fulcrumed in said casing and having an operating portion extending through said aperture, spring means carried within said casing and urging said lever member in one direction, a unitary structure bodily removable through said top wall opening and including a plate-like supporting member, a bimetallic power element carried by the under side of said supporting member within said casing and having an actuating portion engageable with and operable to move said lever member, an electric resistance heater positioned in heat exchange relation with said element, a transformer positioned within said casing and carried by the under side of said supporting member, and means directly connecting together as a unit one terminal of the transformer secondary to one terminal of said heater.
2. In an apparatus of the character described, a supporting member, a switch unit carried by said member and having a reciprocal operating portion, a lever member fulcrumed on said supporting member, a flexible blade having a portion engaging said operating portion, means under stress intermediate said lever member and said blade and exerting a component of force opposing movement of said lever member in one direction, said stressed means acting upon movement of said lever member in said one direction to exert an increasing component of force on said blade thereby to cause said blade to actuate said switch, and means limiting movement of said lever member, said stressed means acting to maintain said opposing component substantially constant within the range of movement of said lever member.
3. In an apparatus of the character described, a supporting member, a switch unit carried by said member and having a reciprocal operating portion, a fulcrum carried by said member, a flexible blade member engageable with said portion and spaced from said fulcrum, a lever fulcrumed on said fulcrum and having a portion overlying said blade member, a spring under com-

pression between said lever portion and said blade member, means holding the end portions of said spring in fixed space positions on said blade member and said lever portion, said lever acting upon movement about said fulcrum to pivot said spring about said blade holding means thereby to decrease its length, said spring having its rate of increase in force with decrease in length so related to the angle formed between said spring and said blade that its component of force tending to flex said blade increases and its component of force tending to oppose movement of said lever remains substantially constant throughout the range of movement of said lever, and means determining said range of movement.

4. In an apparatus of the character described, a supporting member, a lever fulcrumed on said member, a switch unit secured to and movable with said lever, means urging said unit in one direction, an adjustable stop member carried by said supporting member and limiting movement of said unit by said urging means, said unit having a reciprocably movable actuating portion, a fulcrum member rigid with said unit and spaced from said actuating portion, a second lever fulcrumed on said fulcrum member and having a portion overlying and spaced from said actuating portion, a spring, means holding one end of said spring in operative engagement with said actuating portion, and means holding the other end of said spring against movement relative to said lever portion, said spring exerting a force opposing movement of said second lever and acting upon movement of said second lever to actuate said switch unit actuating portion.

5. In an apparatus of the character described, a supporting member, a lever fulcrumed on said member, a switch unit secured to and movable with said lever, means urging said unit in one direction, an adjustable stop member carried by said supporting member and limiting movement of said unit by said urging means, said unit having a reciprocably movable actuating portion, a fulcrum member rigid with said unit and spaced from said actuating portion, a second lever fulcrumed on said fulcrum member and having a portion overlying and spaced from said actuating portion, a spring, means holding one end of said spring in operative engagement with said actuating portion, means holding the other end of said spring against movement relative to said lever portion, said spring exerting a force opposing movement of said second lever and acting upon movement of said second lever to actuate said switch unit actuating portion, and stop means rigid with said switch unit for limiting movement of said second lever.

6. In an apparatus of the character described, a supporting member, a lever fulcrumed on said member, a switch unit secured to and movable with said lever, means urging said unit in one direction, an adjustable stop member carried by said supporting member and limiting movement of said unit by said urging means, said unit having a reciprocably movable actuating portion, a fulcrum member rigid with said unit and spaced from said actuating portion, a second lever fulcrumed on said fulcrum member and having a portion overlying and spaced from said actuating portion, a spring, means holding one end of said spring in operative engagement with said actuating portion, means holding the other end of said spring against movement relative to said lever portion, said spring exerting a force opposing movement of said second lever and acting upon movement of said second lever to actuate said

switch unit actuating portion, a third lever fulcrumed on said fulcrum member and having an aperture therethrough, and an abutment carried by said second lever and extending into said third lever aperture, said abutment being appreciably smaller than said third lever aperture to provide lost-motion between said second and said third levers, said third lever being operable upon movement to engage said abutment for movement of said second lever by said third lever.

7. In an apparatus of the character described, a longitudinally reciprocable operating rod, a spring aligned with and tending to move said rod in one direction, a cam cooperable with and for adjusting said rod against the force of said spring, a lever engageable with said rod, a switch unit having a reciprocable operating member, a lever engageable with first-named lever, and a bodily movable spring interposed between said reciprocable switch operating member and said second-named lever, said bodily movable spring being so positioned and supported that it acts at an acute angle on said switch operating member and exerts a component of force against said second-named lever such that said bodily moveable spring holds said second-named lever against said first-named lever and said first-named lever against said rod.

8. In an apparatus of the character described, a longitudinally reciprocable operating rod, a spring aligned with and tending to move said rod in one direction, a thermostatic power element cooperable with and for adjusting said rod against the force of said spring, electric heating means for said power element, a lever engageable with said rod, a switch unit having a reciprocable operating member, a lever engageable with first-named lever, and a bodily movable spring interposed between said reciprocable switch operating member and said second-named lever, said bodily moveable spring being so positioned and supported that it acts at an acute angle on said switch operating member and exerts a component of force against said second-named lever such that said bodily moveable spring holds said second-named lever against said first-named lever and said first-named lever against said rod.

9. An automatically operable control device comprising supporting means, a longitudinally reciprocal operating rod guided by said means, control means operable by longitudinal movement of said rod, a spring acting on said rod and operable to move said rod longitudinally, a bell-crank lever having one arm engaging said rod in opposing relation to said spring, a helical coil compression spring acting on said lever in opposition to said first-named spring and substantially longitudinally of said arm and exerting a lesser turning moment on said lever than said first-named spring, a shaft carried by said supporting means and extending through and pivotally supporting said lever, said shaft being positioned closely adjacent the line joining the points of engagement of said compression spring and lever and of said lever arm and rod so that the opposing force of said compression spring decreases at a rapid rate upon movement of said rod by said first-named spring, a resilient bimetal controlling member having one end secured to said supporting means and having its other end acting on the other arm of said bell-crank lever and in conjunction with said compression spring, the combined forces of said bimetal member and of said compression spring holding said rod against movement by said first-

named spring, and an electric heating means for said bimetal member to decrease the force exerted by said bimetal member so that said first-named spring will move said rod.

10. An automatically operable control device comprising a longitudinally reciprocal operating rod, control means operable by longitudinal movement of said rod, a spring urging said rod longitudinally, a supporting shaft, a lever journaled on said shaft and having one end engaging said rod to oppose said spring, a spring acting on said lever in opposition to said first-named spring and exerting a lesser turning moment on said lever than said first-named spring, a second lever having a rod engaging end and journaled on said shaft, a spring acting on and urging said second lever in the same direction as said second-named spring urges said first-named lever, stop means to limit rotation of said second lever by said third-named spring, a cross bar loosely interconnecting the other ends of said levers so that said levers can have limited independent rotation, a resilient bimetal member having one end anchored and having its other end bearing against said cross bar, said bimetal member tending to move away from said cross bar on heating and acting when cold to exert its force in conjunction with said second-named and said third-named springs to hold said first-named spring against rod operation and said second-named lever against said stop means, and electric heating means operable to heat said bimetal member so that said first-named spring can overcome said second-named spring and move said operating rod, said bimetal member acting against the mid-point of said cross bar so that the addition of a spring urged control rod acting against said rod engaging end of said second lever with a force equal to the force of said first-named spring will not increase the force tending to overcome said bimetal member.

11. An automatically operable control device comprising a longitudinally reciprocal operating rod, control means operable by longitudinal movement of said rod, a spring urging said rod longitudinally for operation of said control means, a housing member having a top wall opening, a horizontal supporting plate member in said opening, a transformer having a supporting flange seating against and secured to the underside of said plate member, a stop screw adjustably screw-threaded through said flange and extending downward within said housing member, a guide member for said stop screw and carried by said transformer, a resilient bimetal operating member having one end secured to the underside of said plate member, an electric heating coil for said bimetal member and electrically connected to the transformer secondary, a supporting shaft in said housing member, a lever

journaled on said shaft and having an end portion extending out of said housing member into operative engagement with said operating rod to oppose said spring, a spring in said housing member and acting on said lever in opposition to said first-named spring and exerting a lesser turning moment on said lever than said first-named spring, said bimetal member having its free end engaging said lever and acting in conjunction with said second-named spring to hold said rod against movement by said first-named spring, said bimetal member when heated reducing its force against said lever so that said first-named spring can move said rod, and a stop arm on said lever and engageable with said stop screw to limit the movement of said rod by the conjoint force of said bimetal member and said second-named spring.

12. In an apparatus of the character described, a supporting member, a switch unit carried by said member and having a reciprocal operating portion, a lever member having an abutment portion movable transversely to and overlying said operating portion, an abutment member engaging and operable to transmit movement to said switch operating portion, a coil compression spring operable to actuate said switch operating portion and having its ends positioned between and pivotally supported by said abutment portion and said abutment member, said spring urging said lever abutment portion away from alignment with said switch operating portion, and means acting on said lever member and tending to move said abutment portion toward alignment with said switch operating portion so that the force of said coil spring will actuate said switch operating portion.

13. In an apparatus of the character described, a supporting member, a switch unit carried by said member and having a reciprocal operating portion, a lever member having an abutment portion movable transversely to and overlying said operating portion, an abutment member engaging and operable to transmit movement to said switch operating portion, a coil compression spring operable to actuate said switch operating portion and having its ends positioned between and pivotally supported by said abutment portion and said abutment member, said spring urging said lever abutment portion away from alignment with said switch operating portion, an operating spring acting on said lever member and tending to move said abutment portion toward alignment with said switch operating portion so that the force of said coil spring will actuate said switch operating portion, and means controlling the movement of said lever member by said last-named operating spring.

WALTER S. LANDON.
